UNITED STATES PATENT OFFICE.

NAPOLEON CARON, OF NASHUA, NEW HAMPSHIRE, ASSIGNOR OF ONE-HALF TO
NAPOLEON RODIER, OF LOWELL, MASSACHUSETTS.

EYEGLASSES.

1,039,024.

Specification of Letters Patent. Patented Sept. 17, 1912.

Application filed February 13, 1912. Serial No. 677,305.

To all whom it may concern.

Be it known that I, NAPOLEON CARON, a citizen of the United States, residing at Nashua, in the county of Hillsboro and State of New Hampshire, have invented new and useful Improvements in Eyeglasses, of which the following is a specification.

This invention relates to eye-glasses, the object in view being to provide a novel form of mounting for the lenses, whereby all parts of the eye-glasses are held securely together, without the use of the usual screws or other conventional fastening devices, at the same time enabling the parts to be readily disassociated and reassembled, without danger of breaking the lenses. The mountings are of such a simple character that they may be easily and economically stamped up from sheet metal.

With the above and other objects in view, the invention consists in the construction, combination and arrangement of parts, as will be hereinafter more fully described, illustrated in the accompanying drawings, and pointed out in the claims hereunto appended.

In the accompanying drawings: Figure 1 is an elevation of a pair of spectacles or eye-glasses, embodying the present invention. Fig. 2 is an enlarged detail horizontal section through one of the mountings. Fig. 3 is a similar view through one of the end mountings. Fig. 4 is a detail perspective view of the inner or main mounting. Fig. 5 is a similar view of the end mounting. Fig. 6 is a detail perspective view of the spring employed in connection with the inner mounting. Fig. 7 is a similar view of the spring used in connection with the end mounting.

Referring to the drawing, 1 designates the lenses, 2 the nose piece, and 3 the usual bows for securing the spectacles upon the head.

In carrying out the present invention, the nose piece 2 is provided with the angular end portions or terminals 4 which are insertible within the mounting, as will hereinafter appear.

The inner mounting is illustrated in detail in Fig. 4, wherein it is seen to comprise the oppositely arranged parallel bars 5 and 6, and a connecting cross bar 7. At one end, the parallel bars 5 and 6 are bent substan-

tially at right angles to form the arms 8 and 9, and the extremities of these arms are bent inwardly to form studs 10 which enter corresponding holes 11 in the lenses, as shown in Figs. 2 and 3. The other ends of the parallel bars 5 and 6 are bent around or recurved upon themselves to form hooks 12 forming attaching means adapted to receive the angular end or terminal 4 of the nose piece 2, in the manner illustrated in Fig. 2.

In connection with the mounting 4, I employ a spring, comprising a central portion 13 which extends around behind the cross bar 7, and has one end substantially flat, as shown at 14, to bear against the lens 1 and hold the same against the arms 8 and 9 of the mounting and in engagement with the studs 10. The other end of the spring is given a compound bend, so as to embrace the angular end or terminal 4 of the nose piece, said embracing portion of the spring being illustrated at 15.

The end mounting, illustrated in detail in Figs. 3 and 5, corresponds, in the main, with the mounting shown in Figs. 2 and 4, with the exception that the arms 8 and 9 are dispensed with, the other ends of the parallel bars 5' and 6' being bent to form eyes 16 constituting attaching means to receive the pintle 17 of the adjacent bow 3. One of the eyes 16 is extended vertically to form a stop shoulder 17 for limiting the outward movement of the bow 3.

In connection with the end mounting, I employ a spring, the central portion 18 of which passes around behind the cross bar 7', while one end is substantially flat, as shown at 19, to bear against the lens and hold the same against the arms 5' and 6', while the opposite end is recurved, as shown at 20, to engage the pintle 17, the latter being preferably provided with projections or shoulders 21 to prevent the pintle of the bow from becoming disengaged from the spring, after the parts have been adjusted to their proper relation to each other.

From the foregoing description, it will be understood that the spring of each mounting forms and constitutes a key for locking the several parts together, and permitting the same to be taken apart, thereby doing away with the use of the ordinary

conventional screws and like fastenings heretofore used for that purpose. In the inner or main mounting, the angular extremity 4 of the nose piece serves to wedge the spring in place, while in the end mounting the pintle of the bow performs this function.

What is claimed is:

1. An eye-glass mounting, embodying parallel bars, and a cross bar connecting the same, terminal studs on the parallel bars at one end, hooks at the opposite end of the parallel bars, a lens having holes to receive the studs, a nose piece having a terminal 15 shank receivable in said hooks, and a spring key embracing the cross bar with one end bearing against the lens and the other end

engaging the shank of the nose piece and serving to lock all of said members together.

2. An eye glass mounting, embodying parallel bars, a cross bar connecting the parallel bars between the ends thereof, laterally projecting lens engaging studs at corresponding ends of the parallel bars, attaching means at the opposite ends of the parallel bars, and a lens engaging spring removably inserted behind said cross bar and held in place thereby.

In testimony whereof I affix my signature in presence of two witnesses.

NAPOLEON CARON.
